UNITED STATES PATENT OFFICE.

HENRY LOVEJOY, HENRY W. LOVEJOY, AND JAMES H. FERGUSON, OF NEW YORK, N. Y.

IMPROVEMENT IN THE MANUFACTURE OF CURVED ELECTROTYPE AND STEREOGRAPH PLATES.

Specification forming part of Letters Patent No. **86,021**, dated January 19, 1869.

To all whom it may concern:

Be it known that we, HENRY LOVEJOY, HENRY W. LOVEJOY, and JAMES H. FERGUSON, all of the city, county, and State of New York, have invented a new and useful Process of Manufacturing Curved Electrotype or Stereotype Plates, of which the following is a full, clear, and exact description, reference being had to the accompanying drawings, forming part of this specification, and in which—

Figure 1 represents a sectional or edge view of the mold in its flat form, as in the first stage of the process and prior to casting or depositing; Fig. 2, a similar view of the mold in the curved form given to it, as in the second stage of the process and after casting or depositing, with the shell deposited therein, and Fig. 3 an edge view of the finished curved plate.

Similar letters of reference indicate corresponding parts.

By none of the methods heretofore adopted can curved electrotype or stereotype plates be made from flat plates or forms without so altering the size in the direction of the curve that the new or curved plate will not "register" with the original or flat plate or form, whereas it is very desirable in many cases that the flat and curved plates should work together or register with each other—as, for instance, in colored or illuminated printing, and especially so in the printing of the several colors during one passage of the paper.

The object of our invention is to produce the curved plates from the flat plates or forms without altering the length across the face.

To facilitate the explanation of the nature of the invention we will first refer briefly to the well-known previous processes of forming curved electrotype or stereotype plates by way of showing why the same cannot assimilate with the original or flat plates or forms, and of explaining how the difficulty is obviated by our improvement. In one of these processes, after the impression has been taken from the flat plate, the mold has been bent to the full extent of the required curvature to make the curved plate, and then the metal cast or deposited on or in such curved mold. This method shortens the curved plate to an amount dependent upon

the thickness or depth of the mold and degree or extent of its curvature. In another of said processes the "shell" has been made flat in the usual way and then bent to the required extent of the curved plate. This more or less lengthens the shell, according to the curvature and thickness of the shell and character of the surface, a smooth or plain surface not being so much affected as a deeply-engraved one. In the third process the plate has been made flat in the usual way, and then bent to the full curve required. This also lengthens the plate to a degree dependent upon the curvature and thickness of the plate. Our improvement in a measure combines all these three processes. Thus the mold A is made flat in the usual way, as represented in Fig. 1, and afterward is bent to a limited extent short of the full curvature required to be given to the finished curved plate, as shown in Fig. 2. After depositing or casting in this partially-curved mold we further bend the shell or plate B to the full extent of the curvature required for the finished plate, as represented in Fig. 3. Now it will readily be seen that this subsequent bending of the shell or plate has a lengthening effect, which compensates for the shortening effect produced by the bending of the mold, so that the duplicate or curved plate and original or flat one are made to register. The degree of curvature which is given to the mold relatively to the curvature which the finished plate is required to have will depend on the relative thicknesses of the mold or plate; but when molds and plates of ordinary thickness are used we find in practice that the curvature given to the mold should be about half of that which the plate is to have.

In applying this invention to the manufacture of electrotypes the final curvature may be given to the shell before it is backed with the fusible metal or to the plate formed by the backing of the shell with fusible metal.

What we claim, and desire to secure by Letters Patent, is—

1. The process, substantially as herein described, of making curved electrotype or stereotype plates by first forming the impression in a flat mold, afterward giving said mold a

curvature falling short of the required curvature of the bend or duplicate plate to be made, and after casting or depositing in such curved mold, subsequently bending the shell or plate to the full curvature required for the finished and duplicate plate, substantially as specified.

2. Curved electrotype or stereotype plates

made in the manner described, as a new article of manufacture.

HENRY LOVEJOY.
